UNITED STATES PATENT OFFICE.

WALTER B. CROAN, OF CHICAGO, ILLINOIS, ASSIGNOR TO DRYING SYSTEMS, INC., OF CHICAGO, ILLINOIS, A CORPORATION OF ILLINOIS.

SHEET-METAL OIL-BURNING AIR HEATER.

Application filed January 18, 1926. Serial No. 82,026.

The purpose which it is desired to accomplish by means of this invention is mainly to provide a successful and efficient air heating device using oil as a fuel while not requiring a combustion chamber of refractory material or other material which retains such a considerable amount of heat that its life is shortened and it is subject to disintegration, the combustion chamber of the present device being a tube of sheet metal around which air is caused to travel at the correct rate for insuring a safe temperature of the tube irrespective of the immense amount of heat which is transmitted thereby and radiated therefrom. Also by means of the present arrangement the tube is kept at the proper temperature to insure constant and efficient combustion without chilling the flame down to the point where carbon will be deposited. Another aim of the invention is to provide a combustion chamber permitting maximum radiation of heat from its exterior surface so that the heater may be provided with the minimum of heating surface in proportion to the work performed. Other purposes of the invention are to provide a maximum heating surface within the overall dimensions of the device without interfering with convenient assembly thereof while also permitting easy access to the flues for the burned gases.

These objects are successfully accomplished by a construction as shown in the drawings, wherein:

Figure 1 is a longitudinal sectional view in elevation of the oil burning air heater.

Fig. 2 is a plan view with the top cover sheet removed.

Fig. 3 is a front elevation.

Fig. 4 is a sectional view taken on the line 4—4 of Fig. 1.

The construction illustrated in the drawings, is practically wholly formed from sheet metal except where angle irons are necessary for strength and that the casing is formed of blocks of magnesia surrounded by sheet metal for receiving a suitable finishing surface. The only sheet metal found which is capable of withstanding the conditions of operation, of this apparatus is an alloy consisting of iron and chromium. One material suitable for the purpose, principally for the combustion tube is known as duralloy, the characteristics of which are very different from ordinary steel

as it is only to a very slight degree susceptible to oxidation under normal conditions of use and further has the property of taking on a glass-like hardness when slowly cooled from high temperature and is softened by sudden chilling. The sheet metal combustion tube is made the subject matter of a co-pending application for patent, Serial No. 131,889, filed August 27, 1926.

The combustion chamber 1 as shown in the drawings, consists of this material rolled into tubular form, with the meeting edges joined together either by butt-welding or bent over each other to form a seam. At the front end of the combustion chamber is a suitable casting 2 for closing the same except for the inlet air passages and the Venturi-shaped atomizing chamber 3. This chamber is formed by a cylindrical extension 4 of the casting 2 and is lined with a refractory material 5. The fuel atomizing nozzle 6 is supported on the front of the casting 2. The rear end of the combustion chamber is open to a hot gas passageway 7 communicating with a tier of horizontally extending narrow flue-gas passageways 8. At their opposite ends the flue gas passageways communicate with another set of said passageways 9, which serve to conduct the gases of combustion to the cooled gas outlet 10. The gas passageways 8 and 9 are formed of sheet metal, which structure also serves to form alternating sets of air passageways 11 and 12.

The air flows oppositely to the direction of the flue gases, entering the upper set of passageways 11 from the air inlet 13 and then traveling in a reverse direction through the passageways 12 into a vertical air passageway 14 at the rear end of the structure. The air passageway 14 at its lower end communicates with a hot air chamber 15 surrounding the combustion chamber 1. The heated air is finally conducted out of the apparatus through the conduit 16 at the bottom thereof.

The heat of the burning oil in the combustion chamber 1 is sufficient to soon destroy the tube and other parts of the structure if it were not for the cooling action of the air traveling through the apparatus and around the combustion tube oppositely to the direction of flow of the burned gases. It is therefore essential that when the oil burner is set into operation that the required flow of air be at once initiated and

continued during the operation of the oil burner. The cooling effect of the air maintains the tube within the permissible temperature limits, irrespective of the fact that 5 the tube is functioning to transmit and radiate into the air an enormous quantity of heat for the available radiating surface thereof. The sheet metal tube presents a glowing hot surface to the air traveling 10 therearound and is a good conductor of heat, and in this respect differs from many combustion chambers lined with refractory material and of course having a greatly 15 lessened capacity for heat radiation possible with the sheet metal structure.

In the operation of the device, the air to be heated is first set in motion or at least simultaneously with the ignition of the fuel, and of course during the normal operation 20 of the oil burner, must at all times be pumped through the apparatus at the required rate to keep the sheet metal surfaces thereof at a safe temperature. The air enters through the inlet 13 traveling along the 25 set of passageways 11 and then the set 12, downwardly through the passageway 14 and into the chamber 15 where it rises due to its temperature and flows around the combustion tube 1 and finally downward at the 30 front end of the apparatus and out through the passageway 16, from which the heated air is conducted to the place of use thereof. The products of combustion leave the tube 1 at its rear end traveling in an opposite direction upwardly through the passage 7 and then along the passageways 8 and 9 to the 35 cooled gas outlet 10.

By the arrangement shown, the heated air is successively subjected to higher and 40 higher temperatures while the oppositely flowing combustion gases successively come

into contact with surfaces of continuously lessened temperature. Therefore, the maximum amount of heat is extracted from the combustion gases since, although these gases 45 may be considerably cooled when nearing the outlet, they are then in contact with the surfaces subjected to the cooling action of the air when at its lowest temperature.

Although but one specific embodiment of 50 this invention has been herein shown and described, it will be understood that numerous details of the construction shown may be altered or omitted without departing from the spirit of this invention. 55

I claim:

1. An oil burning air heater comprising a sheet metal structure forming a combustion chamber and a plurality of narrow flue gas passageways communicating with the 60 combustion chamber and alternating with narrow passageways for air, means forming an air space surrounding the combustion chamber, and said air space being in communication with said air passageways. 65

2. An oil burning air heater comprising a sheet metal structure forming a combustion chamber and a plurality of narrow flue gas passageways communicating with the combustion chamber and alternating with 70 narrow passageways for air, means forming an air space surrounding the combustion chamber, said air space being in communication with said air passageways, air intake means communicating with said narrow 75 passageways for air and air outlet means communicating with the space surrounding the combustion chamber.

Signed at Chicago this 8th day of January, 1926.

WALTER B. CROAN.
